BODY FOR FERTILIZER SPREADERS
OR THE LIKE

Loren E. Tyler, Benson, Minn.

Filed Apr. 27, 1962, Ser. No. 69,877

Term of patent 14 years

(Cl. D35—2)

FIG.1

FIG.2

FIG.3

FIG.4

FIG.5

FIG. 1 is a top plan view of a body for fertilizer spreaders or the like embodying my new design;

FIG. 2 is a left side elevational view thereof;

FIG. 3 is a right side elevational view thereof;

FIG. 4 is a front elevational view thereof on a smaller scale; and

FIG. 5 is a rear elevational view thereof on a smaller scale.

The fragmentary broken line showing of a trailer body chassis in the several views is for purposes of illustration only.

I claim:

The ornamental design for a body for fertilizer spreaders or the like, as shown and described.
